UNITED STATES PATENT OFFICE.

ARTHUR W. SMITH, OF GLOUCESTER, MASSACHUSETTS.

HOT-AIR FURNACE.

1,368,768.

Specification of Letters Patent. Patented Feb. 15, 1921.

Application filed April 27, 1920. Serial No. 376,906.

To all whom it may concern:

Be it known that I, ARTHUR W. SMITH, a citizen of the United States, residing in Gloucester, in the county of Essex and State 5 of Massachusetts, have invented an Improvement in Hot-Air Furnaces, of which the following description, in connection with the accompanying drawings, is a specification, like characters on the drawings representing

10 like parts.

This invention relates to portable hot air furnaces and has for its object to provide a simple, efficient and inexpensive furnace which is capable of being assembled as a 15 unit at the place of manufacture, shipped to the job and installed by unskilled labor in a minimum of time, and with a minimum of labor.

The invention also has for its object to 20 provide a furnace of the character described, which is adjustable in height, as will be described.

To this end, the portable furnace is provided with a strong, light base, preferably 25 of wrought iron, a heating element attached thereto to be supported thereon and a casing inclosing the heating element and attached to the said base to be supported by it.

In the preferred form of furnace, the casing 30 may be provided with a movable section capable of being adjusted without change in construction to fit cellars or rooms having ceilings of different heights, and provision is made for effecting an air tight joint between 35 the stationary casing and its movable section in the adjusted positions of the latter.

These and other features of this invention will be pointed out in the claims at the end of this specification.

40 Figure 1 is a vertical section of a hot air furnace embodying this invention.

Fig. 2, a like section taken at right angles to the section shown in Fig. 1.

Fig. 3, a section like Fig. 2 with the movable sections raised or extended.

Fig. 4, a horizontal section taken on the line 4—4, Fig. 1.

Figs. 5 and 6, details of the tight joint to be referred to.

50 Figs. 7, 8, 9 and 10, modifications to be referred to.

In Figs. 1 to 4, is shown a preferred construction of air furnace embodying the in-

vention, which is provided with a base 10, preferably a plate of wrought iron, a heating element 12 which is permanently secured to the base plate 10 as by rivets 13, and a casing 14, preferably of sheet metal, which incloses the heating element 12 and is permanently secured to the base plate 10 as by 55 rivets 15, so that these three elements and any parts supported by them are movable as one piece.

The heating element may be of any suitable or usual construction and is shown as a 60 coal burning element, it being provided with a fire box 16 having a lining 17 of fire resisting material, a grate 18, a fuel inlet 19 normally closed by a fire door 20, an ash pit 21, provided with a door 22, and a smoke 65 outlet 23, which leads to the outside of the furnace and which is preferably provided with a baffle or deflector 24 to cause the products of combustion to pass upwardly 70 toward the top 125 of the heating element 75 before passing out through the outlet 23.

The casing 14 surrounds the heating element and is preferably made of sufficient height to extend above the top of the heating element, and has coöperating with it 80 means for separating the space between the heating element 12 and the casing 14 at its sides or ends into passages 25, 26, which communicate with each other near the bottom of the furnace. In the present instance, 85 the casing 14 is made substantially oblong in shape, see Fig. 4, with the side or end walls of the casing separated from the heating element a materially greater distance than the front and rear walls of said casing, and each 90 of the spaces between the side walls and the heating element is separated into the passages 25, 26 by stationary partition plates or walls 30 which are firmly secured to the front and rear walls of the casing 14 to be supported thereby with their lower ends separated from the base 10. The casing 14 and walls 30 being of sheet metal are conventionally 95 shown. The stationary walls of the casing 14 have coöperating with them movable front and rear walls 31, 32 and side or end walls 33, 34, which are designed to form extensions of the casing, and the partition walls 30 have coöperating with them movable walls 35 which are designed to form 100 extensions of said stationary partition walls.

These movable walls are designed to be connected together so as to be moved as one piece, which may be effected as herein shown by connecting the front and rear movable walls 31, 32 of the casing by cross bars or pieces 36 to which the movable partition walls 33 are secured.

The movable extensions 33, 34 of the casing coöperate with the movable extensions 10 35 of the partition walls 30 to form extensions of the passages 25, and the movable extensions 35 of the partition walls coöperate with the front and rear walls 31, 32 to form an extension of the space 38 above the heating element with which space the passages 26 communicate.

The movable extensions 35 of the stationary partition walls 20 may and preferably will be provided with inwardly inclined 20 portions 39 to provide the extensions of the passages 25 with enlarged upper ends, through which cool air enters the said passages and is drawn down toward the bottom of the furnace and then ascends through the 25 passages 26 in contact with the heating element and into the space 38 above the latter, and from which space the heated air passes out of the furnace.

Provision is made for effecting air tight 30 or substantially air tight joints between the movable section of the casing and the stationary section thereof, and between the movable sections of the partition walls and the latter.

This result may be accomplished by providing the movable sections of both parts with packing members 40 which may be of asbestos or other suitable material and which may be a folded strip of the same as shown 40 in Fig. 5 or a single piece as shown in Fig. 6. The packing members 40 are carried by the movable sections and are designed to bear against the stationary sections with which they coöperate so as to make a tight joint therewith and thus insure that the cooler air shall pass through the heated passage 26 for the full length of the same. The packing members 40 carried 50 by the movable extensions 35 of the partition walls may be pressed into engagement with the stationary partition walls 30 by spring members, shown as metal strips 41 attached to the movable extensions 35 and having their free ends bearing against the stationary sections of the casing 14.

In the construction shown in Figs. 1 to 4, the inlet passages for the cool air are within the outer casing 14 and are designed to coöperate with suitable openings in the floor 42 of the room above the cellar or other place where the furnace is located, which openings are located on opposite sides of an opening with which the hot air outlet 38 coöperates, and said openings are 65 normally covered by the usual registers, a

large register 43 covering the air outlet and smaller registers 44 covering the air inlets, see Fig. 3.

In practice, the furnace is assembled in the shop or factory complete with the movable sections in their closed up position represented in Figs. 1 and 2. The furnace is shipped in this condition to the house or other building in which it is to be installed and is placed in the cellar on the floor 75 thereof, below and in line with the openings in the floor 42. The floor of the cellar is represented in Fig. 3 by the line 100. When thus placed in position an unskilled mechanic or other person can remove the 80 registers and reach down through the opening in the floor thus un-covered and draw the movable sections of the furnace up into position with the mouths of the air inlet 85 passages and the mouth of the air outlet 90 passage in close proximity to the first floor, and may secure the movable sections in fixed position by screws, nails or other devices 45 which are passed through the movable section of the casing 14 into the floor joists 46 or 95 other stationary part of the building, after which the register is placed in position and the furnace is ready for use. It will thus be seen that skilled labor is not required to install the furnace, but that the latter can be installed by unskilled labor without trouble and in a minimum of time. It will also be observed, that the furnace is assembled in the factory or shop as a unit ready for use, and does not require to be altered or changed in 100 construction by skilled labor to adapt it to the particular job, but merely requires that the extension members be drawn up into operative position with relation to the openings in the floor.

The furnace is particularly designed as a heating plant for small houses, bungalows and like buildings, and it may be preferred to make it oblong in cross section as shown in Fig. 4 to obtain a furnace of maximum 110 capacity which can be carried through the ordinary doorway.

In the construction shown in Figs. 1 to 4, the cool air from the room above the floor 42 passes down through the passages 115 25 and up through the passages 26 into the space 38 and then up into the room, as indicated by the arrows in Fig. 3.

As represented in Figs. 1 to 4, the furnace is provided with a single movable extension of the casing and partition walls, but it is not desired to limit the invention in this respect, as it may be provided with an extension composed of a plurality of members as represented in Figs. 9 and 10, 125 wherein the extension of the casing is shown as composed of two members 50, 51 and of the partition walls of two members 52, 53, which members are movable with relation to each other and to the stationary members 130

with which they coöperate and are suitably interlocked by flanges 54, 55 so as to telescope in a manner well understood. Suitable packing like that shown in Fig. 5 or 6 is employed between the interlocking flanges to obtain air tight joints between coöperating sections or members.

In the furnace as thus far described, the air inlet passage is within the stationary 10 casing and formed by partition walls 30 therein, but it is not desired to limit the invention in this respect, as the air inlet passage may be located outside of the casing as represented in Figs 7 and 8, wherein the air 15 inlet passage 25 is shown as formed by a stationary pipe 60 attached at its lower end to the stationary casing and in open communication with the latter near the lower end of the same, and having telescopically 20 connected with its upper end a movable pipe section 61 which is capable of being drawn up from its normal position shown in Fig. 7 into its operative position shown in Fig. 8, the movable section 62 of the casing being 25 similarly connected with the stationary member 63 of the casing and movable with relation thereto from its normal position shown in Fig. 7 into its operative position shown in Fig. 8. It will be understood that 30 air tight joints are formed between the movable sections 61, 62 and the stationary sections 60, 63 by suitable packing members as above described.

It will be observed that the furnace shown 35 in Figs. 7 and 8 can also be assembled in the shop as a unit ready to be installed by unskilled labor on the job.

If desired or required, suitable braces or stops, not shown, may be used to prevent the 40 parts of the furnace from separating, and heat resisting material 70 may be used on the walls of the space 38 to reduce the fire hazard.

Claims:

- 45 1. In a hot air furnace, in combination, a supporting base, a heating element and a stationary casing for said heating element attached to said base to be transported therewith as a unit, stationary partition walls 50 within said stationary casing forming air passages, a movable section of said casing co-operating with the latter to form an extension thereof, movable partition walls co-operating with said stationary walls to form 55 extensions thereof, and means for effecting
- substantially air tight joints between said movable extensions and the stationary members with which they coöperate.
2. In a hot air furnace, in combination, a supporting base, a heating element and a stationary casing for said heating element attached to said base to be transported therewith as a unit, and an extensible section for said casing attached to the latter to move therewith as a unit and adjustable thereon 60 without change in construction thereof.
  3. In a hot air furnace, in combination, a supporting base, a heating element and a stationary casing for said heating element attached to said base to be transported therewith as a unit, an extensible section for said casing attached to the latter to be moved therewith as a unit and adjustable thereon 65 without change in construction thereof, and a packing member between said stationary 70 casing and its extensible section to form a substantially tight joint.
  4. In a hot air furnace, in combination, a base, a stationary casing attached thereto and open at its upper end, a heating 75 element located in said casing and separated therefrom to form an air space between the same, said heating element being attached to said base and non-communicating with said casing and provided with a smoke outlet independent of said casing, and a movable casing member coöperating with said stationary casing and in sliding engagement therewith to form an extension of said stationary casing and of the said air space. 80
  5. In a hot air furnace, in combination, a supporting base, a heating element attached thereto, a substantially oblong casing surrounding said heating element and attached to said base to be moved with the latter and 85 the heating element as a unit, stationary walls supported by said casing and interposed between the sides of the latter and said heating element to form air inlet and outlet passages within the casing, a movable 90 casing section coöperating with said stationary casing and movable partition walls coöperating with said stationary partition walls, and means for connecting said movable partition walls with said movable casing section to move with the latter. 95

In testimony whereof, I have signed my name to this specification.

ARTHUR W. SMITH.
